UNITED STATES PATENT OFFICE.

JOHANNES RUTHS, OF DJURSHOLM, SWEDEN, ASSIGNOR TO AKTIEBOLAGET VAPOR-ACKUMULATOR, OF STOCKHOLM, SWEDEN, A CORPORATION OF SWEDEN.

STEAM ACCUMULATOR PLANT.

Application filed April 18, 1925. Serial No. 24,144.

My invention relates to steam accumulator plants and provides means to conduct steam from a steam chamber, both to an accumulator and to low pressure conduit, while the pressure in the chamber is sometimes the same as the accumulator pressure and at other times the same as that in the low pressure conduit. The invention will be understood by reference to the accompanying drawings in which Figure 1 shows an arrangement according to my invention including a reducing valve and a check valve working in parallel and Figure 2 shows an arrangement where the check valve and reducing valve are combined into a single valve.

In Figure 1, 10 represents a steam chamber, for example, an extraction chamber between stages of a motor. Chamber 10 is supplied with steam in any desired manner. 11 represents an accumulator connected in parallel to conduit 12. 13 represents a low pressure conduit supplying steam to a consumer 14. Conduits 12 and 13 combine to form a conduit adapted to supply steam from the accumulator 11 to the low pressure consumer 14. In the conduit 12 are a reducing valve 15, which may be of any desired construction and operates in known manner to increase the area of steam flow through the same upon decrease of actuating pressure and a valve 16 which may be of any type and which controls the flow of steam to the low pressure conduit. Valve 15 is set to open at a given value of pressure which is somewhat below the normal working value of pressure in chamber 10 and low pressure conduit 13. Check valve 17 in conduits 18 arranged parallel to reducing valve 15 operates to allow flow in direction toward the accumulator, but prevents flow from the same to the consumer. Pipe 19 connects chamber 10 with conduit 12 between valves 15 and 16, and between check valve 17 and valve 16.

Steam of any variable or constant rate depending on the particular plant passes from chamber 10 through pipe 19 and either to consumer 14 or accumulator 11 or to both depending upon the relative steam consumption and steam supply. If the supply of steam from chamber 10 is greater than that

required by the low pressure consumer, the surplus passes through check valve 17 and into the accumulator to be stored. The pressure in pipe 19 and in chamber 10 will at such time be the same as the pressure in the accumulator, and increase as the accumulator pressure increases during charge. Suppose now that the supply from chamber 10 decreases while the flow through valve 16 remains substantially unchanged. The pressure decreases in chamber 10 and pipe 19 and that portion of conduit 12 which is between the valves 15 and 16 until a greater pressure 55 prevails in the accumulator than in pipe 19, at which time check valve 17 will close, and the pressure in pipe 19 will fall to substantially the pressure of the low pressure conduit 13. If the supply of steam through 70 pipe 19 is less than what is needed by the low pressure consumers, the pressure decreases so low that valve 15 opens and allows steam to pass from the accumulator through conduit 12 and into conduit 13 to 75 the low pressure consumer 14. Thus when the accumulator discharges the pressure in chamber 10 is substantially equal to the pressure in low pressure conduit 13, although a higher pressure prevails in the 80 accumulator. As the amount of steam supplied from chamber 10 again increases at a rate faster than the low pressure consumption, valve 15 first closes, and then valve 16 must be decreased in flow area 85 and becomes the controlling element for the passage of steam to the low pressure conduit, and when the pressure in chamber 10 has risen to a small increment above the accumulator pressure, check valve 17 opens 90 and steam flows to the accumulator.

By means of this arrangement the conduit 18 can be of inconsequential length, wherefore pipe 12 serves both to conduct steam to the accumulator from chamber 10 95 and from the accumulator to the low pressure consumers, thereby simplifying the plant considerably in cases where the accumulator is at a considerable distance from the chamber 10.

Figure 2 shows an arrangement where the check valve and reducing valve 15 are combined into a single valve 15^a and the manually controlled valve 16 of Fig. 1 is

replaced by a reducing valve 16^a which operates in known manner to maintain a constant pressure behind the same. Valve 15^a is controlled by piston 20 moving in cylinder 21 and acted upon by spring 22. Fluid under pressure is supplied to chamber 24 through pipe 25 in which is a restriction 23 and which has an opening 26 therein through which the pressure fluid can flow out and which opening is controlled by a baffling member 27. This baffling member 27 is attached to an arm 28 rotatable about a fixed pivot 29 and acted on by spring 30.

Pressure on the accumulator side of valve 15^a is transmitted through tube 42 to chamber 31 between bellows 32 and diaphragm 33, and pressure on the consumer side of valve 15^a is transmitted through tube 43 to chamber 34 between bellows 35, and diaphragm 33. The two bellows and the diaphragm 33 are connected as indicated at 36. Diaphragm 33 is moved in accordance with the difference of pressures on the two sides of the valve 15^a, and this movement is transferred to lever 28 by means of rod 37 which is made of two parts loosely abutting each other. This mechanism takes the place of the check valve.

Diaphragm 38 is acted upon by pressure in chamber 39 transmitted through tube 40 from the consumer side of valve 15^a, and movement of diaphragm 38 is transmitted to lever 28 by means of bracket 41, the right hand end of which partially encircles rod 37 but does not touch the same except that when moved a given distance to the left it is adapted to contact an abutment 44 on rod 37.

The operation of the arrangement is as follows:—

When the pressure on the consumer side of valve 15^a is greater than on the accumulator side, this being the condition when there is a surplus supply of steam from chamber 45 10 over the momentary consumption in the low pressure line, diaphragm 33 is moved to the left as shown in the figure, whereby lever 28 is rotated above pivot 29 and baffling member 27 checks the outflow of fluid 50 through opening 26, whereby pressure is built up in conduit 25 and consequently in chamber 24 and piston 20 is moved against the action of spring 22 to the right as shown in the figure, whereby valve 15^a is opened 55 more or less to allow flow of the surplus steam into the accumulator.

Now if the pressure on the consumer side of valve 15^a drops, due to increased consumption over supply, the pressure in chamber 60 31 predominates over the pressure in chamber 34 and diaphragm 33 is moved to the right thereby allowing lever 28 to be moved under the action of spring 30 to increase the opening in conduit 25, so that more 65 fluid flows out, and the pressure in chamber

24 is thereby reduced so that piston 20 moves to the left and valve 15^a is closed. Upon further decrease of pressure below that at which reducing valve 16^a is completely open, diaphragm 38 is flexed so far to the left due to the decrease of pressure transmitted through tube 40 that the right hand end of bracket 41 contacts abutment 44, moving the same to the left and checking the outflow through opening 26, so that piston 20 is moved to the right and valve 15^a opened. This mechanism then operates in the same manner as reducing valve 15 of Figure 1. The action of diaphragm 38 and associated parts in opening valve 15^a is independent of the action of the diaphragm 33 and associated parts since when bracket 41 contacts and moves abutment 44 to the left, the two parts of rod 37 separate and movement of diaphragm 33 has no effect on the regulation.

Having thus described my invention what I claim is:—

1. In a steam plant, in combination, a steam chamber, a low pressure consumer, an accumulator, a conduit adapted to conduct steam both in direction from said accumulator toward said consumer and in direction from said consumer to said accumulator, a valve in said conduit operated by the pressure on the consumer side of the same, a second valve in said conduit to control flow of steam to said consumer, a pipe extending from said chamber to said conduit at a point between said valves, and valve mechanism to allow passage of steam from said pipe to said accumulator when the pressure in said chamber exceeds the pressure in the accumulator.

2. In a steam plant, in combination, a steam chamber, an accumulator, a consumer, a single conduit adapted to conduct steam from said accumulator toward said consumer and in direction from said consumer to said accumulator, a valve in said conduit, a pipe extending from said chamber to said conduit at a point on the consumer side of said valve, mechanism to actuate said valve responsive to difference of pressure in the conduit on the two sides of the valve and operating to allow flow of steam to the accumulator when the pressure in said chamber exceeds the pressure in said accumulator and a second mechanism to actuate said valve responsive to pressure on the consumer side of said valve and operating to allow flow of steam from said accumulator and through said valve upon decrease of actuating pressure below a given value independently of the action of the first mentioned mechanism.

3. In a steam plant, in combination, a steam chamber, a low pressure consumer, an accumulator, a conduit connecting said accumulator with said consumer, a pipe connecting said chamber with said conduit,

means to control flow of steam in said conduit from the point of connection of said pipe toward said accumulator and from said accumulator toward said point of connection so that when steam pressure in said chamber is higher than in said accumulator, steam flows from said chamber through said conduit to said accumulator and when steam

pressure in said chamber falls below a predetermined value, steam flows from said accumulator through said conduit to said consumer. 10

In testimony whereof I hereunto affix my signature.

JOHANNES RUTHS.
